UNITED STATES PATENT OFFICE.

WALTER L. PIPES, OF ELIZABETH, NEW JERSEY, ASSIGNOR TO THE SHOE HARDWARE COMPANY, OF WATERBURY, CONNECTICUT, A CORPORATION OF CONNECTICUT.

MULTIPLE FASTENING DEVICE.

Application filed July 24, 1928. Serial No. 124,759.

This invention relates to separable fasteners and particularly to that type of fastener for overshoes, garments, automobile curtains, and other purposes where two stringers are locked 5 and unlocked by a sliding cam device, the locking being effected by travel in one direction and unlocking by an opposite movement.

The object of the invention is to provide a simple locking device, which may be small 10 and which will be light in weight, easy to manufacture, and which is adapted to give a particularly strong, flexible union.

A feature of the invention is the warped shape of the engageable members which 15 causes them to be particularly well adapted to resist lateral displacement, at the same time allowing the completed fastener to be more readily flexed longitudinally.

According to the present invention, the 20 locking members are all alike and are therefore interchangeable. The stringers may be of any suitable type but preferably consist of a fabric tape having a beaded or corded edge upon which the locking members are clamped. 25 The locking members consist of contractible jaw portions adapted to be clamped upon the tape and engageable portions which are arched longitudinally and warped transversely. The members secured to one stringer 30 alternate with those on the other stringer so that when the sliding device is moved back and forth the locking members will be engaged and disengaged according to the direction of movement.

The invention resides particularly in the 35 form of the engageable portions of the locking members, the doubly curved surface of which is novel and especially well adapted for the many uses when an unusual degree of 40 strength is required of the fastener. Longitudinal curving or arching of the members enables them to engage easily and prevents their longitudinal disengagement when so interlocked. The transverse warping of the 45 surfaces of each member causes them to be doubly bound together, preventing their lateral disengagement. Because of their curved surfaces, the members are adapted to slip over one another to a slight degree without risk 50 of disengaging, thus increasing the flexibility of the fastener.

Referring now to the drawings:

Fig. 1 is a perspective view on an enlarged scale of a fastener embodying this invention.

Fig. 2 is a cross-section on the line *a—a* of Fig. 1.

Fig. 3 is a transverse section of the locking members.

Fig. 4 is a longitudinal section of the locking members showing their staggered arrangement; and

Fig. 5 is a detailed view of one of the locking members.

Referring to Fig. 1, it will be seen that the stringers 1—1 have at their abutting edges 5 beads 2 upon which the interlocking members are securely fastened. While the locking members may of course be secured to the fabric in other ways, this has been found to be the preferred method. The stringers may be secured together at one end by a fastening link such as 3 and will have suitable stopping members such as 4 at the opposite end to limit the movement of the slider. A sliding cam operating device 5, many varieties of which are well known, is mounted on both stringers. Preferably it will be Y-shaped, branches 6 being each separately mounted on a stringer, thus forming a guide or tongue which upon movement in one direction serves to engage the locking members, but upon movement in the other direction to disengage them. The slider may be operated by means of a ring 7 secured to the slider by rivet 8.

Fig. 5 represents one of the locking members, having a slotted portion which consists of the jaws 9, and an engageable portion which is curved and warped both transversely and longitudinally. The engageable member is arched longitudinally in the manner of the fastener disclosed in a copending application but the feature is added of warping the member transversely, thereby greatly increasing its binding properties. Since it has been found that where a considerable number of engageable members are joined together a very slight curvature is sufficient to give a very firm lock, the design of this type of engageable member may be comparatively simple. Because of the warp or doubly curved characteristic of this type of engageable member, a fastener made up therewith is particularly well adapted for certain uses, as for example where considerable lateral strain is to be expected.

An understanding of the shape of the engageable portions 10 of the interlocking elements may be best had by reference to Figs.

3, 4 and 5 of the drawings. In Fig. 3 which is a transverse section of a series of engageable portions of the elements it is shown that the curvature of the interengageable portions 5 is concave downwardly in the plane of the section. Examination of Fig. 4 which is a longitudinal section of a series of the elements shows that the engageable portions have a curvature which is convex downwardly in the 10 plane of the section. Fig. 5 is a perspective view of the element and the shading on this view clearly shows the double curvature nature of the upper surface of the engageable portion of the element. The lower surface 15 of the engageable portion in the particular embodiment disclosed herein has the same geometrical form as the upper surface.

Having thus described my invention what I claim as new and useful and desire to protect by Letters Patent is:

- 20 1. In a fastener, a number of engageable members adapted to interlock, each of the engageable surfaces of each member being curved both concavely and convexly.
- 25 2. In a fastener, a number of engageable members adapted to interlock, each of the en-

gageable surfaces of each member being curved both concavely and convexly, the engageable portion of each member being of uniform thickness.

30 3. In a fastener, a number of engageable members adapted to interlock, each of the engageable surfaces of each member being curved both concavely and convexly, the engageable surfaces being continuous and extending to the edges of the member.

35 4. In a fastener, a number of engageable members adapted to interlock, each of the engageable surfaces of each member being curved both concavely and convexly, the engageable surfaces of each member being of like geometrical form.

40 5. In a fastener, a number of engageable members adapted to interlock, each of the engageable surfaces of each member being curved both concavely and convexly, the members being interchangeable.

45 Signed at New York, county of New York, State of New York, this 13th day of July, 1926.

WALTER L. PIPES.
